UNITED STATES PATENT OFFICE.

ABEL H. FROST, OF CHICAGO, ILLINOIS.

GUIDE FOR WEAVING COILED-WIRE FABRIC.

SPECIFICATION forming part of Letters Patent No. 464,693, dated December 8, 1891.

Application filed April 13, 1891. Serial No. 388,687. (No model.)

To all whom it may concern:

Be it known that I, ABEL H. FROST, a citizen of the United States, residing at Chicago, in the county of Cook and State of Illinois, 5 have invented certain new and useful Improvements in the Manufacture of Coiled-Wire Fabric; and I do hereby declare the following to be a full, clear, and exact description of the invention, such as will enable 10 others skilled in the art to which it appertains to make and use the same, reference being had to the accompanying drawings, and to letters of reference marked thereon, which form a part of this specification.

15 This invention relates particularly to means for guiding the coils in machines for weaving coiled wire.

The invention has no bearing upon the coil-forming mechanism. Any of the well-known 20 forms of mechanism for this purpose may be used in connection with my improved guides, the specific purpose of the guides being only to direct the course of the coils after they leave the coil-forming mechanism and to hold 25 the last of the finished coils in suitable position for the intertwining of the coil being projected from the coil-forming mechanism.

In the accompanying drawings, Figure 1 is 30 a section in line *a b* of Fig. 2, looking toward the left, in which my improvement is applied to a pair of jaws. Fig. 2 is a plan. Fig. 3 is a detail view of a portion of said jaws. Fig. 4 is an end view of a pair of rolls embodying my improvement. Fig. 5 is a side view of a 35 portion of said rolls. Fig. 6 is a longitudinal vertical section through said rolls.

In Fig. 1, A is the bed of the table, supporting the jaws B and C. Said jaws have their mouth directed upward and are as long as 40 the fabric to be woven, and they may be made separable in any suitable manner. The drawings show the jaw B bolted rigidly to the table A by bolts B', while the jaw C is hinged to said table. Posts A' rise from the table 45 near the jaw C, and expanding springs A², located between said posts and the upper end of said jaw, press the latter normally against the jaw B. The lever C' is applied to said jaw C in such manner as that it may be 50 pressed down to draw the upper portion of

said jaw away from the jaw B. These jaws are preferably made to meet face to face. When so made there is obviously no clear space between said faces for the passage of coils, but for each coil there is a spiral passage D through the material of the jaws, such 55 passage having its axis in the joint between the two jaws and being larger in cross-section than the wires of the coil, so that there will not be any material friction in the movement of the coil through said spiral passage. When thus constructed, a half of each of said 60 spiral passages is in each jaw, and when the jaws are separated the inner face of each shows rows of oblique cavities, as in Fig. 3. 65 These coils are usually formed of two wires projected simultaneously and side by side; but these wires sometimes separate and diverge in the ordinary machines; but it will be seen that in these complete spiral passages 70 the wires will not thus diverge. On the other hand, they are held together throughout the entire length of the machine. The path of the coil being formed always links through the path of the last-finished coil. This must 75 be the case when the coil being formed intertwines at each turn with the last-finished coil. Hence the adjacent spiral passages D are 80 made to intertwine; but they do not communicate with each other. Each is a distinct passage by itself, and the new coil, in passing onward between the jaws, cannot take a wrong course, because every attempt to move laterally is met by the wall of the passage through which it is moving. Thus 85 the forward end thereof can never hit the last-finished coil and divide or be deflected by the latter. The progress of the coil being formed is as definite and restricted as though the last-finished coil were not near it. Furthermore, if the pitch of the coil being formed 90 varies a little, the coil is compelled to travel over the space measured by the spiral passage. If the pitch is slightly increased, so as to lengthen the coil, the walls of the spiral 95 passage retard the forward end of the coil and make it travel over the spaces measured by the turns of the spiral passage, and if the coil is slightly shortened by decrease of pitch the walls of the spiral passage tend to ex- 100

tend the coil to the standard made by the spiral passage. The spiral passage holding the last-finished coil also performs an excellent function in that it holds the last-finished 5 coil in a fixed and definite position with reference to the path to be traversed by the coil being formed. It will be seen that the movement of the coil being formed is made definite in every respect, and that it cannot fail 10 to properly intertwine with the last-finished coil, and that the two wires of which the coil is composed cannot diverge. When a coil has been finished, it is severed between these 15 jaws and the coil-forming mechanism by hand-nippers or by any of the automatic cutting mechanism heretofore devised. Then the jaws are separated and the fabric raised by hand or by mechanism, so that the last-finished coil will rest in the spiral passage 20 next the lowest, the latter being left empty. The new coil is then projected into the lower passage and the fabric again raised.

In Fig. 4 a pair of rolls E are provided around their peripheries with oblique cavities, forming complete spiral passages D between the meeting portions of such peripheries. The cavities may be so arranged as to form two complete spiral passages between the rolls. In operation a coil is first projected 25 into the passage farthest to the left in Fig. 4. Then the rolls are turned in the direction indicated by the arrows, so that the coil is shifted toward the right and a new spiral passage is formed at the left. Then another 30 coil is projected into the new spiral passage and made to intertwine with the first coil. Then the rolls are again turned in the direction indicated by the arrows, so that both coils are shifted to the right, and still another 35 spiral passage is formed at the left. Then another new coil is projected through the spiral passage now at the left and made to intertwine with the latter of the two previously-made coils. Then the rolls are again 40 shifted and more coils added in the same way. 45

It is deemed unnecessary to show the manner of mounting and progressing these rolls, because fluted rolls or rolls having projections 50 upon their peripheries have been heretofore used to hold and progress coiled-wire fabrics.

I claim as my invention—

1. A guide for weaving coiled-wire fabric, which guide consists of two meeting separable faces having a spiral passage interlinking 55 with the space to be occupied by the last-finished coil and having its axis in the joint between said faces, substantially as shown and described.

2. A guide for weaving coiled-wire fabric, 60 which guide consists of two meeting separable faces having interlinking spiral passages whose axes are in the joint between said meeting faces, substantially as shown and described.

65 3. A guide for weaving coiled-wire fabric, which guide consists of two separable jaws

meeting face to face and having a spiral passage extending through them and interlinking with the space to be occupied by the last-finished coil and having its axis between 70 the faces of said jaws, substantially as shown and described.

4. A guide for weaving coiled-wire fabric, which guide consists of a stationary jaw B and a movable jaw C, held normally in contact with the jaw B by springs A², said jaws having a spiral passage extending through and interlinking with the space to be occupied by the last-finished coil and having its axis between the meeting faces of said jaws, 80 substantially as shown and described.

5. A guide for weaving coiled-wire fabric, which guide consists of a stationary jaw B and a hinged jaw C, held normally in contact with the jaw B by springs A², said jaws having a spiral passage extending through and interlinking with the space to be occupied by the last-finished coil and having its axis between the meeting faces of said jaws, 85 substantially as shown and described.

6. A guide for weaving coiled-wire fabric, which guide consists of a stationary jaw B and a movable jaw C, held normally in contact with the jaw B by springs A², said jaws having a spiral passage extending through 95 and interlinking with the space to be occupied by the last-finished coil and having its axis between the meeting faces of said jaws, and a lever attached to said movable jaw for moving the latter, substantially as shown and 100 described.

7. A guide for weaving coiled-wire fabric, which guide consists of a stationary jaw B and a hinged jaw C, held normally in contact with the jaw B by springs A², said jaws having a spiral passage extending through and interlinking with the space to be occupied by the last-finished coil and having its axis between 105 the meeting faces of said jaws, and a lever attached to said hinged jaw for moving 110 the latter, substantially as shown and described.

8. A guide for weaving coiled-wire fabric, which guide consists of a face having oblique cavities suitably located to receive one side 115 of a coil, and a second face arranged opposite said first-mentioned face in suitable proximity to the latter to confine the turns of said coil in said oblique cavities in said first-mentioned face, there being a suitable passage 120 or opening between said faces and extending into the cylindric space of the passage formed by said oblique cavities and said second-mentioned face to allow a second coil to lie parallel to and be intertwined with the path of 125 said first-mentioned coil, substantially as shown and described.

9. A guide for weaving coiled-wire fabric, which guide consists of a face having two rows of oblique cavities, one of said rows being in line with the axis of the coiler and 130 said cavities being of proper length and suit-

ably spaced to receive and inclose the turns of two intertwining coils of the fabric, and a second face arranged opposite said first-mentioned face in suitable proximity to the latter to confine the turns of said coils in said oblique cavities in said first-mentioned face, substantially as shown and described.

In testimony whereof I affix my signature, in presence of two witnesses, this 6th day of April, 1891.

ABEL H. FROST.
